Mich., assignors to American Seating Company, Grand
Rapids, Mich., a corporation of New Jersey

Filed Feb. 24, 1961, Ser. No. 64,043

Term of patent 14 years

(Cl. D5—4)

Fig. 1

Fig. 2

FIGURE 1 is a perspective view of a hospital bed showing the new design, the head section of the bed being shown in an upwardly inclined position in this view;

FIGURE 2 is an end elevational view as seen from the foot of the bed, the entire bed and all parts thereof being shown in fully lowered position in this view;

FIGURE 3 is a side elevational view of the bed in elevated position, with the head section upwardly inclined and with the knee section upwardly bowed; and

FIGURE 4 is a side elevational view showing the bed and all of its parts in fully lowered positions.

The side of the bed which is not shown is like the side of the bed which is shown, and the back of the headboard which is not shown is substantially plain.

We claim:
The ornamental design for a hospital bed, substantially as shown and described.
